UNITED STATES PATENT OFFICE

EDWARD F. CHAFFEE, OF SYRACUSE, NEW YORK, ASSIGNOR TO THE O. M. EDWARDS COMPANY INC., OF SYRACUSE, NEW YORK, A CORPORATION OF NEW YORK

SHEET METAL SASH AND VENTILATOR

Application filed May 4, 1927, Serial No. 188,616. Renewed November 21, 1930.

This invention relates to window sashes having ventilators built therein and has for its object, a particularly simple and efficient ventilator by which dust is excluded at all times from entering the interior sash member either when the ventilator is opened or closed.

It further has for its object a particularly simple, efficient and economical construction by which the ventilator is assembled in the sash member.

The invention consists in the novel features and in the combinations and the constructions hereinafter set forth and described.

In describing this invention reference is had to the accompanying drawings in which like characters designate corresponding parts in all the views.

Figures 1 and 2 are fragmentary views illustrating a sash in opposite elevations.

Figure 3 is a sectional view on line 3—3, Figure 1.

Figures 4 and 5 are opposite side elevations of the detached ventilator member, partly broken away.

Figure 6 is an end elevation of the detached ventilator member.

This invention comprises a window sash having a hollow sash member as a hollow bottom rail formed with openings in its opposite walls and a ventilator member slideable in the hollow sash member and having openings therethrough movable into and out of register with the openings in the contiguous walls of the sash member and also having a screen which is carried by the ventilator member and moves therewith and which covers said openings at the outer side of the sash member whereby the openings are covered at all times by the screen.

1 designates the sash and 2 the bottom rail which is usually formed up of sheet metal to have opposing walls 3 which are formed with ventilator openings or slots 4 therethrough, the bottom rail being formed with a reentrant groove 5 along one edge for receiving the margin of the glass pane 6. The rail 2 is here shown as in inverted U shape in general form with its lower edges turned in to form flanges 7 at 50 for interlocking with a weather strip

or buffer 8. Preferably the bottom rail also has an internal strip 9 extending lengthwise thereof near its lower edge and forming a guide for the ventilator member to be presently described.

10 designates the ventilator member which slidably fits in the sash member 2 and slides along the strip 9, it having a wall movable along the inner face of one of the opposing walls of the sash member and formed with 60 openings therethrough which are movable into and out of register with the openings 4 in the contiguous wall of the sash member.

11 is the screen which is carried by the sliding ventilator member covering the openings therethrough. The ventilator member is also formed with a flange which extends into one of the spaces at the side of the re-entrant groove 5.

In the illustrated embodiment of my invention, the ventilator member is of double construction and in the form of a box, the opposing walls 12 of which slide along the inner faces of the walls 3 of the sash member and the margins 13 of which extend into the 75 spaces on opposite sides of the reentrant groove 5. The walls 12 are formed with openings 14 therethrough movable into and out of register with the openings 4 in the walls 3 of the sash member. The screen 11 is carried 80 on the inner side of one of the walls to cover the openings therein and this screen is preferably located toward the outer side of the sash in order to not only exclude the dust from entering the car but also from entering 85 the hollow sash member. Heretofore, the openings toward the outer side of the sash have been open and the screen covered only the openings on the inside of the sash and hence the hollow sash member filled up with 90 dust, snow, etc., oftentimes preventing the operation of the ventilator.

The opposing walls 12 constitute two spaced apart members positioned in the bottom rail against the walls of the bottom rail 95 and provided with openings therein for registration with the openings in the walls of the rail. The intermediate part or bottom wall of the boxlike structure provides one means for maintaining the opposing walls or spaced 100

apart members in properly spaced relation. Also, the flanges or margins 13 which extend into the spaces on opposite sides of the re-entrant groove 5 constitute another means for maintaining the opposing walls or members 5 12 in properly spaced relation.

Preferably in order to hold the ventilator member from rattling, it is provided with a spring runner 15 along the edge thereof contiguous to the strip 9, this runner being 10 here shown as a leaf spring secured between its ends to the ventilator member, the end portions of the spring flaring outwardly. By reason of the arrangement of the spring, the ventilator slides evenly without binding.

15 The spring runner 15 constitutes means carried by the ventilator member 10 for holding the ventilator member 10 against rattling by pressing it edgewise in a direction at an angle to its sliding movement, and holding 20 the margins 13 in the grooves or spaces at opposite sides of the reentrant groove 5. Each margin or flange 13 and the space in which it is located constitute in effect a coacting tongue and groove extending lengthwise of 25 the ventilator member.

The ventilator member is operated by a handle 16 located on the inside of the sash and having a stem 17 extending through a 30 lengthwise slot 18 in the inner wall 3 of the sash member or bottom rail and threading into the ventilator member or a block therein.

Owing to the arrangement of the screen and to the fact that it is part of the ventilator member and slides therewith, the openings 35 on the outer side of the sash member, as well as on the inner side, are always protected against the passing of dust, snow, etc., therethrough. The fitting of the flanges of the 40 ventilator member into the spaces at one or both sides of the re-entrant groove of the sash and the sliding of this ventilator member on the bottom strip of the sash provides a particularly simple and inexpensive assembly of 45 the sash and the ventilator member.

What I claim is:

1. The combination of a window sash having a hollow member formed with openings in its opposite walls, a ventilator member 50 slidable in the hollow sash member and having opposing walls formed with openings movable into and out of register with the openings in the sash member and a screen covering the openings in one of said walls of the ventilator member.

2. The combination of a window sash having a hollow sash member formed with openings in its opposite walls, a hollow ventilator member slidable in the hollow sash member 60 and having openings in its opposing walls movable into and out of register with the openings in the sash member and a screen within the hollow ventilator member and covering the openings in one of the walls thereof.

3. The combination of a window sash hav-

ing a hollow member formed with a reentrant groove along one edge thereof for receiving the margin of the glass pane and with spaces between the side walls of the groove and the inner faces of the opposing walls of the sash member, the sash member having openings in its opposing walls, a ventilator member slidably fitting the sash member and having openings movable into and out of register with those of the sash member, the ventilator member also having flanges extending into the spaces at opposite sides of the reentrant groove. 70

4. The combination of a window sash having a hollow member formed with a reentrant groove along one edge thereof for receiving the margin of the glass pane and with a space between one of the side walls of the groove and the opposing wall of the sash member, the sash member having openings in its opposing walls, a ventilator member in the general form of a box, the front and rear walls of which slidably fit the inner faces of the front and rear walls of the sash member and having openings movable into 80 and out of register with those of the sash member, the ventilator member having a flange slidably in one of the spaces at one side of the reentrant groove. 85

5. The combination of a window sash having a hollow sheet metal member formed with a reentrant groove along one edge thereof for receiving the glass pane and with a space between one side of the groove and the inner face of the opposing wall of the sash member, and also being provided with an internal transverse wall extending lengthwise thereof near the outer edge of the sash member, the sash member being formed with openings in its opposing walls, a ventilator member 95 slidable fitting in the sash member on one of the opposing walls thereof and said transverse wall and being formed with a flange extending into said space at one side of the reentrant groove, the ventilator member 100 also having openings movable into and out of register with the openings in the sash member. 105

6. The combination of a window sash having a hollow sheet metal member formed with a reentrant groove along one edge thereof for receiving the glass pane and with spaces between the sides of the groove and the inner faces of the opposing walls of the sash member, the sash also being provided with 115 an internal transverse wall extending lengthwise thereof near the outer edge of the sash member, the sash member being formed with openings in its opposing walls, a ventilator member 120 slidable fitting in the sash member and engaging the opposing walls thereof and said transverse wall, the ventilator member being formed with flanges extending into the spaces on opposite sides of the reentrant groove, the ventilator member also having 125 130

openings movable into and out of register with the openings in the sash member.

7. The combination of window sash having a hollow sheet metal member formed with a reentrant groove along one edge thereof for receiving the glass pane and with spaces between the sides of the groove and the inner faces of the opposing walls of the sash member, the sash member being provided with an internal transverse wall extending lengthwise thereof near the outer edge of the sash member, and being formed with openings in its opposing walls, a ventilator member slidably fitting in the sash member and engaging the opposing walls thereof and said transverse wall, and being formed with flanges extending into the spaces on opposite sides of the reentrant groove, the ventilator member also having openings movable into and out of register with the openings in the sash member and a screen located within the ventilator member and covering the openings in one of the walls thereof.

8. In a sash ventilator, a hollow sash rail provided with openings in the walls thereof, two spaced members positioned in the rail against the walls thereof and provided with openings therein for registration with the openings in the walls of the rail, means for maintaining the members in properly spaced relation, and means for shifting the members to move the openings therein into or out of register with the openings in the walls of the rail.

9. In a sash ventilator, the hollow sash member provided with openings in the opposing side walls thereof, a ventilator member slidable in the hollow sash member and provided with openings movable into and out of register with the former openings, and spring means for holding the ventilator member from looseness in the sash member, the spring means comprising a runner at one lengthwise edge of the ventilator member and tending to thrust the ventilator member edgewise in the hollow sash member in a direction at an angle to the direction of the sliding movement.

10. The combination of a window sash having a hollow member formed with openings in its opposite side walls, a ventilator member slidable in the hollow sash member and having openings movable into and out of register with the openings of the sash member, the sash member being formed with a reentrant groove along one edge for receiving the margin of the glass pane and with internal spaces at opposite sides of the side walls of the groove and the sash member having flanges extending into said spaces, and spring means acting on the sash member to thrust the same edgewise and hold the flanges in said spaces.

11. The combination of a window sash having a hollow member formed with openings

in its opposite side walls, a ventilator member slidable in the hollow sash member and having openings movable into and out of register with the openings of the sash member, the sash member being formed with a reentrant groove along one edge for receiving the margin of the glass pane and with internal spaces at opposite sides of the side walls of the groove, and the sash member having flanges extending into said spaces, and spring means acting on the sash member to thrust the same edgewise and hold the flanges in said spaces, the spring means comprising a runner carried by the edge of the sash member opposite to that at which the flanges are provided and sliding on an edge wall of the hollow sash member.

12. The combination of a window sash having a hollow member formed with openings in its opposing walls, a ventilator member slidable in the hollow sash member and having openings movable into and out of register with the former openings, the ventilator member and the sash member having a slidably interlocking tongue and groove extending lengthwise of the ventilator member, and spring means tending to thrust the ventilator member edgewise and hold the tongue and groove in sliding engagement.

13. The combination of a window sash having a hollow member formed with openings in its opposing walls, a ventilator member slidable in the hollow sash member and having openings movable into and out of register with the former openings, the ventilator member and the sash member having a slidably interlocking tongue and groove extending lengthwise of one edge of the ventilator member, and the spring means tending to thrust the ventilator member edgewise and hold the tongue and groove in sliding engagement, said spring means comprising a runner carried by the ventilator member at the edge thereof opposite to that along which the tongue and groove are located, the runner coacting with an internal edge wall of the hollow sash.

14. The combination of a window sash having a member formed with openings in its opposing walls, a ventilator in said member for opening and closing said openings, the ventilator member including a slide for opening and closing said openings, and spring means carried by the slide and acting edgewise thereon for holding it from rattling.

15. The combination of a window sash having a member formed with openings in its opposing walls, a ventilator in said member for opening and closing said openings, the ventilator member including a slide for opening and closing said openings, guide means for the slide, and flat spring means carried by, and extending lengthwise of the slide and pressing against the guide and slidably along

the same for holding the slide from rattling
in the guide.

In testimony whereof, I have hereunto
signed my name, at Syracuse, in the County
of Onondaga, and in the State of New York,
5 this 29th day of April, 1927.

EDWARD F. CHAFFEE.
